UNITED STATES PATENT OFFICE.

CLAYTON F. WIEST AND JACOB L. WIEST, OF YORK, PENNSYLVANIA.

BOX-TRAY MACHINE.

SPECIFICATION forming part of Letters Patent No. 681,601, dated August 27, 1901.

Application filed March 21, 1901. Serial No. 52,256. (No model.)

To all whom it may concern:

Be it known that we, CLAYTON F. WIEST and JACOB L. WIEST, citizens of the United States, residing at York, in the county of 5 York, State of Pennsylvania, have invented certain new and useful Improvements in Box-Tray Machines, of which the following is a specification, reference being had therein to the accompanying drawings.

10 This invention has relation to box-machines, and particularly to that class of machines intended for the manufacture of that portion of sliding match-boxes which is known as the "tray," although the invention is not confined to the manufacture of boxes or trays 15 for the specific purpose mentioned.

Among the objects of the invention is to construct a machine of this class which shall be as simple as possible, contain a minimum 20 number of parts or elements arranged in a compact manner, but which shall perform its functions smoothly, accurately, and without undue strain upon any of its working or stationary elements.

25 Furthermore, it is intended that the invention shall be capable of receiving the straw-board or any other suitable material from which the trays are to be made in the form of a web or continuous strip and to paste, 30 punch, score, cut off, fold, dry, and deliver successive portions of the continuous strip or web, whereby boxes or trays are formed and delivered from the machine automatically.

35 Other objects and advantages of the invention will hereinafter appear in the following description, and the novel features thereof will be particularly pointed out in the appended claims.

40 Referring to the drawings, Figure 1 is a side elevation of a complete machine constructed in accordance with the invention. Fig. 2 is a vertical longitudinal substantially central section of a portion of the machine 45 embodying the invention. Fig. 3 is a perspective of a portion of the punching and cross-scoring cross-head. Fig. 4 is a similar perspective of the reciprocating cutter. Fig. 5 is a perspective of one-half of the separable 50 former and its adjuncts. Fig. 6 is a perspective of the folding-fingers separated from the former. Fig. 7 is a side elevation of a strip-

per separated from the former. Fig. 8 is an enlarged detail, partly in section, of the pasting mechanism. Fig. 9 is a plan of the principal operative elements of the machine co-operatively arranged. Fig. 10 is a plan of the material as it appears after the successive operations of the principal operative devices, and Fig. 11 is an elevation of the gearing employed for giving motion to the principal operative devices of the machine. Fig. 12 is a detail of one of a pair of levers employed.

Like letters of reference indicate like parts throughout the several figures of the drawings.

Upon any suitable framework A there is arranged a bed A', within and upon which are mounted punching and cross-scoring mechanism B, longitudinal scoring mechanism C, feeding mechanism D, cut-off mechanism E, and folding mechanism F, in the order mentioned and shown and in the order of the progress of the material through the machine.

Referring to Fig. 10, X represents the continuous strip of material from which boxes or trays are to be made; X', the cross-score; X², openings formed by the punching devices; X³, the longitudinal scoring, and X⁴ the line of severance upon which blanks X⁵ are separated from the continuous strip, so that said blanks embody end flaps X⁶ and corner flaps X⁷, which after the end flaps are folded on the lines X' are secured within and at the corners of the box or tray, as clearly shown at the left of Fig. 10. It is understood that the progress of the material through the machine is by a step-by-step or intermittent feed regulated to move the material a box-blank length at each feed thereof, whereby the cut-off severs a blank at the center of the openings X², formed by the punches, and between the two score-lines X', so that the folding mechanism, being properly timed with relation to the feed of the material, produces a complete box or tray at each reciprocation of the former element of the folder mechanism.

Within the upright gibs B' is a vertically-reciprocating head B², carrying punches B³ and transverse creasers B⁴, secured to the head B² by bolts B^{4X}. Suitable gibs or wearing-plates B⁵ and set-screws B⁶ for the same are provided to take up the wear of the parts,

as is usual in this class of machinery. B⁸, Fig. 2, represents a stripping-plate, beneath which the material passes and serves to hold the material down during an upward stroke 5 of the punches and creasers to strip the material from those devices. A die-block B⁹ (see dotted lines in Fig. 2) is supported in the bed and directly below the punches, which block, in connection with the punches, 10 serves to remove portions of the material to form the openings X², Fig. 10, in the usual manner. In suitable bearings C' in the bed of the machine and in the standards mounted thereon in advance of the punching-head are 15 the longitudinal creasing or scoring rollers or disks C², which by means of the bearings and adjusting-bolts C³ are caused to grip the material so as to be rotated thereby and to form the longitudinal score-lines X³.

20 D D represent feed-rollers mounted in suitable bearings and adjusted by bolts D' as to their pressure or grip upon the material, so as to feed the same. These feed-rollers are geared together, as shown at D², Fig. 1, 25 and are driven by a ratchet D³ and pinion, the latter meshing with the gear D² and arranged upon the stud D⁴ with the ratchet, which is operated by a pawl D⁵, carried on the free end of the lever D⁶, which by a rod 30 or pitman D⁷ is driven by means and in a manner hereinafter described.

The cut-off mechanism comprises upright bearings E and gibbs and adjusting-screws E' for a reciprocatory cutter-head E², into the 35 lower edge of which at a recess E³, Fig. 4, is screw-threaded or otherwise suitably secured a pitman or connecting-rod L⁴ for reciprocating the cutter-head by means hereinafter to be described. Upon the face of the cutter- 40 head is secured the blade E⁶, (by means of screws or bolts E^{6X},) which is adapted in a downward reciprocation of the rod to sever a blank from the web. Between the cutter-head and the feed-rolls there is arranged a 45 plate, rod, or bar E⁴, which lies just above the material for the purpose of preventing the same from bending or buckling up at the time a cut is made by the knife E⁶. By means of the bolts E⁷ and slots E⁸, Fig. 9, the cutter- 50 head and its adjuncts are adjustable longitudinally on the bed for the purpose of determining the exact length of the blanks to be severed.

The folding mechanism of the machine comprises a reciprocating former F', conforming in its outline and proportions to those of the tray to be made by the machine. This former is secured by bolts F² to a cross-head F³, connected by a pitman or rod F⁴ to mechanism, hereinafter described, for giving the necessary reciprocating movement to the former. The cross-head is supported in standards F⁶, rising from the bed of the machine and slotted, as at F⁷, for the passage therethrough 60 of the cross-head and for its connection F^{5X} to pitman F⁴.

In the bed of the machine and immediately

below the former F' is an opening F⁸, practically of the contour of the box to be made. Supported from the bed of the machine and 70 depending in the opening F⁸ there is arranged a folding-box F⁹, formed in two sections, each similar to the other, one being shown with its adjuncts in Fig. 5. Each section comprises end and side walls conforming to the 75 size and contour of the box to be made and having at its side wall a projecting bracket F¹⁰, with apertures for the passage of bolts F¹¹ for securing the folding-box to the bed of the machine. Within the edge of the side 80 wall there is mounted for oscillation a rod or bar F¹², having fingers F¹³ extending therefrom, and at each end folding-blades F¹⁴. Suitable springs F¹⁵, secured to the blades and to the bracket, as clearly shown, serve 85 to maintain the folding-blades in a vertical position when not otherwise operated upon, as hereinafter described. Recesses F^{13X} receive the fingers F¹³ when in a vertical position. 90

F¹⁶ represents strippers for holding a tray against being carried upwardly by the former-head F' as it returns from its lowest position in its operation. Each of the strippers consists of a beveled face latch-like head F¹⁶, formed 95 upon or secured to a spring F¹⁷, Fig. 7, secured to the outer surface of the forming-box, the head passing through the openings therein, the normal tendency of the spring being to project the strippers inwardly beyond the 100 surface of the box and to permit their outward movement when the former-head descends within the box, and at its lowest position the strippers are spring-pressed against the former-head above the edge of the box or 105 tray thereon, so as to retain the same against upward movement. The folding-box is of such a depth as to retain within a desired number of trays for the purpose of holding the glued flaps at the corners in contact with 110 each other until they become set or dried. It will be seen that as each successive tray is forced into the folding-box by the forming-head a tray will be forced out of the lower end of the box, the intermediate trays 115 remaining therein for the purposes stated. As each tray is forced from the box it falls upon an inclined shelf F¹⁸, which conducts it upon the floor or into any suitable receptacle. To adapt the folding-box to material which varies more or less in thickness and to insure setting the glued flaps firmly together, there are provided at each of the corners and near the top of the folding-box spring-pressed pressure-rollers F¹⁹. Mounted upon shafts F²⁰ in 125 elongated bearings F²¹ and against the shafts are arranged the ends of springs F²², secured in any suitable manner, as at F²³, to the outer surface of the box. By this means contact of the periphery of the rolls with the corners 130 of the tray or box while on the forming-head as it descends into the box is assured, notwithstanding variations in thickness of the material of which the tray is formed. As be-

90 95 100 105 110 115 120 125 130

fore stated, the folding-box is formed in two sections, one of which is shown in Fig. 5, and the two assembled are shown in Fig. 9, F^{24} being the line of junction between the two sections of the box. Forming the folding-box in sections gives several advantages over constructing the same integral, and among them are the facility in manufacturing the same, in applying the adjuncts thereto, and the adjustment of the two sections toward and from each other by forming slots instead of cylindrical holes for the securing-bolts F^{11} in a manner well known to the mechanic. By this means and by the employment of a coöperating forming-head boxes of different widths may be folded.

The pasting mechanism employed in this invention comprises a paste vessel G , mounted upon a shelf-support G' , which in turn is mounted upon brackets G^2 , employed for supporting the roll of strawboard X . Upon each of the brackets G^2 there is a standard G^3 for the support of the oscillating paste-dauber G^4 , having paste-applying projections G^5 . These projections G^5 are spaced apart, so as to apply paste upon the continuous strip of strawboard in two spots, which may or may not, as desired, be spread by a movement of the web at the time the paste is applied, and which spots occur in the progress of the work of the machine at opposite sides of the line of severance and at opposite ends of the end flaps X^6 , so that when the blank is folded the flaps X^6 come against the spots or strips of paste or glue which is applied by the points G^5 of the dauber. A rock-arm G^6 , rigidly connected with the shaft of the dauber, is pivotally connected to a connecting-rod G^7 , which in turn is connected with a moving part of the machine G^8 for giving the desired movement to the dauber. A plate or shelf H extends from side to side of the machine and has its receiving end curved downwardly, as at H' , to prevent injuring the web of material by said plate, and also has sides H^2 , which may be adjustably secured to the plate in any suitable manner to adapt it to webs of different widths. The principal function of the plate H is to flatten and guide the web to the guiding-roll H^3 , this being one of a series for conducting the web upwardly outwardly along over the glue or paste box (arranged near the end of the bed of the machine on a bracket extending therefrom) and to the principal operating devices thereof. At the point where the paste is applied to the web there is a cross-bar H^4 , mounted in any suitable manner on the extension or bracket H^5 , which constitutes an extension of the bed of the machine, and to this bar is secured a plate H^6 , having depending sides for the purpose of alining the web while passing beneath the plate, which thus forms a bed or support for the web at the time paste or glue is applied by the dauber G^4 .

It now remains to describe the mechanism for giving the various principal elements of

the machine their necessary motions in the relatively proper time. As the feed of the material is intermittent and extends during a time necessary to present the blank length of material to successively arrange devices operating thereupon, it will be seen that the various operations must take place at one time—that is, during the interim between the feeding operations. For this purpose the transmission of motion to the principal operating devices of the machine is accomplished by the employment of two shafts, a main shaft from which the longer movements of the former-head and feeding devices are operated and a directly-connected counter-shaft bearing a cam, which is embraced by a pivoted lever that extends beyond the cam, so that the cutting and punching devices may be connected to said lever, the former to the extension of the lever at one side of the cam and the latter at the other side of the cam and between it and the pivot of the lever, by reason of which construction and arrangement practically direct connection is secured and only a slight movement is given, just such as is required to punch and sever the thin material operated upon. Furthermore, these two shafts, with the extended cam-embracing lever, give a balanced smooth even operation of all the parts, none of which is overloaded.

The feeding element of the machine is operated by driving the connecting-rod D^7 from a wrist-pin D^8 , projecting from a slotted block D^9 , secured in any desired position diametrically by a bolt D^{10} to a disk D^{11} on the main shaft of the machine, guides or ways D^{12} on said disk serving to guide the wrist-pin block D^9 radially in all of the adjustments thereof. By means of this adjustable connection the throw of the pawl-lever D^6 may be varied to cause the feed-rolls D to feed more or less of the material at each rotation of the main shaft. The main shaft is provided with fast and loose pulleys I of usual construction and connection. The connecting rod or rods F^5 , depending from the cross-head, carrying the forming-head F' , are adjustably connected with the strap J' of the eccentric J , mounted on the main shaft by means of its threaded end and a nut F^{5x} thereon, whereby the throw of the forming-head may be adjusted in its limits. A gear K is mounted upon the main shaft and meshes with a companion gear K' , mounted on a counter-shaft K^2 , whereby rotary motion is conveyed from the main shaft to the counter-shaft. Upon the counter-shaft is mounted the cam K^3 , which works in a lever L , having a yoke L' . (See dotted lines in Figs. 1 and 11.) The lever is continued beyond its yoke and, as at L^2 , pivotally connected by a strap L^3 to the connecting-rod L^4 , which extends to the cutter-head E^2 . It is understood that the various connecting-rods thus far described are duplicated, one being at each side of the machine, and that the eccentric and lever L and cam K^3 are also du-

licated in order to give and obtain parallelism in the draft, strain, working, and work of the principal working devices to which the connecting-rods are attached. The connecting-rod G^7 of the dauber is attached, as at G^8 , to the periphery of the eccentric-strap J' . Now it will be noticed that as the main shaft revolves the eccentric J gives vertical reciprocation to the forming-head F' , and by means of the gears K and K' , cam K^3 , and lever L the cutter-head and the punching-head are given reciprocation by means of the devices L^2 , L^3 , and L^4 for the cutter-head, L^5 , L^6 , and L^7 for the punching-head, and through the medium of the connecting-rod G^7 the paste or glue dauber is operated, and these reciprocatory motions and the operation of the dauber take place at such time in the rotation of the main shaft as is occupied by the feed-pawl D^3 in moving backward and downward upon the ratchet preparatory to producing a subsequent feed of the material, and, further, that during said further subsequent feed of the material the principal operating devices—those which reciprocate—are being elevated from the material ready for a repetition of their functions.

The provision of a proper tension device which shall act positively and regular regardless of the amount of material in the roll from which the web is being drawn by the machine is an essential feature of construction in order to produce regularity in the sizes of the product of the machine. A tension device performing this important function is shown at N , and it comprises a leather or other suitable fiber or textile pad arranged to bear against the web while on the first guide-roll H^3 . (See Fig. 1.) This pad extends throughout the width of the web and is carried by levers N' , one at each end of the pad, and connected by a plate N^2 , which serves as a backing or support for the pad as well as a spacer or connecting-bar for the two levers N' . These levers may be pivoted in the framework at N^3 or in boxes or bearings secured thereto, and they extend beyond said pivotal support, and upon the extensions N^4 a weight (or it may be a spring secured to any fixed part of the frame) is connected. It will now be seen that regardless of the quantity of material upon the roll the resistance of the tension device upon the web as it enters the machine is uniform at all times and under all circumstances.

The operation of this machine will be readily understood by those skilled in the art. At each progressive step of the material through the machine the punching mechanism B forms the openings X^2 and the cross-scoring X' , and at the same time the cutter severs a blank from a continuous web along the line X^5 and simultaneously a previously-severed blank is forced by the forming-head F into the forming-box, the overreaching side and end laps of the blank being turned by the edges of the folding-box in the opening

F^8 . As the forming-head descends it brings the bottom of the blank in contact with the fingers F^{13} , and these cause a rotation of the shaft F^{12} , thereby bringing into operation the folding-blades F^{14} , which carry the end laps X^7 inwardly in advance of folding the end laps X^6 , and afterward are returned to their normal vertical position by means of the springs F^{15} . The spring-pressed rolls F^{19} now act upon the outer surface of the end flap X^6 at the point where paste has been applied and forcibly presses these parts together and against the ends of the forming-head, which carries the box or tray down below the stripers F^{16} , they yielding for the passage of the tray, returning to their normal position after its passage, grasp its upper edges at opposite sides and near the corners and retain it within the folding-box as the forming-head ascends. Successive trays are formed until in the operation of the machine a tray is discharged as each successive tray is formed and introduced into the box.

Various changes in proportions and details within the skill of any person conversant with box or tray machines may be made without a departure from the principle of the invention, and it is therefore not limited in this regard.

What we claim is—

1. In a machine of the class described embodying punching, feeding, cutting and forming mechanisms, the combination therewith of a main shaft and a directly-connected counter-shaft provided with a cam, a pivoted, cam-embracing, lever, rods connecting the forming and feeding mechanisms with the main shaft, and rods connecting the punching and cutting mechanisms with said lever the latter being pivoted at one end to the framework and extending beyond the counter-shaft and adapted to embrace a cam thereon, the point of connection of the last-mentioned rods being at opposite sides of said counter-shaft; substantially as specified.

2. In a machine of the class described, the combination with punching devices and cutting devices arranged in the order named, of a lever pivoted at one end and formed with a yoke and an extension beyond said yoke, a shaft carrying a cam located within said yoke, a rod extending from the lever at a point between its yoke and pivot to the said punching devices, and a rod connecting said cutting devices with the extension of said lever; substantially as specified.

3. In a machine of the class described and in combination with a guide-roll for the web, of a tension device comprising a pad arranged to bear against the web on said guide-roll, a support for said pad, and levers for said support pivoted to the frame of the machine, and a weight secured to extensions of said levers; substantially as specified.

4. In a machine of the class described, a folding-box formed in sections, each section comprising a side wall and portions of the end walls, and means for rigidly and adjustably

supporting each section upon the bed of the machine; substantially as specified.

5. A folding-box section comprising a side wall and portions of end walls having vertical and transverse slots in combination with seam-pressing rollers and shafts for the same, the former located in the vertical slots and the latter in the horizontal slots of said end walls; substantially as specified.

10. 6. A folding-box section comprising a side wall and portions of end walls, the latter having vertical and transverse slots in combination with seam-pressing rollers located in said vertical slots and shafts for the same located 15 and capable of bodily movement in said transverse slots, and springs arranged to bear on each end of each shaft; substantially as specified.

7. A folding-box formed in sections, each 20 of which is provided with transverse shaft F^{12} having folders and fingers F^{13} and recesses F^{13x} for said fingers; substantially as specified.

8. A folding-box section comprising an at-

taching-bracket, a side wall having recesses 25 for the folder shaft and fingers, strippers working through openings in said wall and an end wall with elongated bearings for a seam-pressing roller; substantially as specified.

30 9. A folding-box formed of two sections each having a supporting-bracket, a side wall with openings and strippers projecting there-through and portions of end walls having mounted in recesses therein seam-pressing 35 rollers, shafts for the same mounted in transverse slots, springs carried by each section and bearing on the ends of said shafts, and means for rigidly securing each section to the bed of the machine; substantially as specified. 40

In testimony whereof we affix our signatures in presence of two witnesses.
